SPENCER HEATH, OF ELKRIDGE, MARYLAND.

AIRCRAFT-ENGINE CONTROL.

Application filed November 21, 1923, Serial No. 676,190. Renewed May 16, 1927.

This invention relates to engine control and has special reference to aircraft engines in connection with variable or reversible pitch propellers or with other mechanism in accordance with the operation of which it is desired to control the power and speed of the engine by regulating the admission of fuel or by other means of engine control.

One object of this invention is to provide engine control means directly responsive to changes taking place in other mechanism, such as a variable pitch propeller, gear shift, or reversing gear mechanism or mechanism responsive to variations in the speed of travel.

A further object is to provide engine control means directly responsive to changes taking place in other mechanism and also responsive to manual means of control without necessity of disengaging either control means in order to allow free operation of the other.

A further object is to provide combined automatic or mechanical and manual control means.

A further object is to provide combined automatic and manual control means in which the manual control serves to fix the engine speed or the speed of travel and the automatic control serves to hold the engine or the vehicle at or near the speed so fixed.

With these objects in view and further objects to appear as my invention is fully disclosed I have invented the engine control shown by the annexed drawings which illustrate one of the forms in which my invention may be embodied and in which:

Figure 1 is a side view of my invention as employed to insure safety of engine speed.

Fig. 2 is a side view as applied to obtaining uniform speed of travel through engine control.

Fig. 3 is a plan view of Fig. 2.

Fig. 4 is a diagrammatic side view as applied to the combined functions of Fig. 1 and Fig. 2.

Referring to the drawings, 1 is the carburetor containing a throttle valve opened and closed by movement of the arm 2. The arm 7 mounted on shaft 8 is variable in position in accordance with any change of pitch in the propeller blades or any engaging or disengaging of transmission or reverse gears.

21 (Fig. 1) is a shaft connected with the

operating mechanism of a reversible propeller (or with a reversing gearing). This shaft carries a cam 20 which moves the arm 7 through the cam roller 19. This cam 20 is so cut and adjusted that roller 19 will be farthest from the cam center at the moment when the propeller is at zero pitch (or the reverse gearing is in neutral position) and nearest to the cam center when the propeller is in full pitch, either forward or reverse (or when the gearing is in mesh).

Movements of arm 7 are communicated to the throttle valve arm 2 through rod 9, lever 10 and rod 11 as shown, the mid portion of lever 10 being fulcrumed at 18 on the end of rod 12. The rod 12, passing through the guide 17, is connected at 13 with the arm 3 mounted on shaft 4 which carries the sheave 5 for manual throttle control by the cables 6 which are connected with any customary form of throttle lever convenient to the pilot's hand.

The dotted line 15 connecting the throttle valve arm 2 with the end of the arm 3 shows the position of the customary linkage when manual control of the engine alone is employed. My combined manual and automatic control is effected by dispensing with the customary direct connection along the line 15 and connecting the throttle valve arm 2 with the arm 3 by means of rod 11, lever 10 and the sliding rod 12 connected to arm 3 at 13 which is nearer to the center than the point of connection 14 of the original connection along the line 15. By this means the throttle arm 2 may be made to respond to manual control through rod 12, when no movement is taking place in arm 7, in precisely the same manner as though it were transmitted through a connection along the line 15, with this advantage, however, that when any movement takes place in arm 7, due to a change of propeller blade pitch, shifting of transmission gears or the like, this change, acting through the rod 9 moves lever 10 about its fulcrum 18 and thus, through rod 11, communicates a change to the throttle valve arm 2.

As applied in connection with a variable and reversible pitch propeller the arm 7 is so arranged that when the propeller blades approach their position of zero pitch the arm moves in the direction of the arrow C. This causes, through rods 9 and 11 and lever

10, a sufficient movement of throttle arm 2 to partially close the throttle and thus either diminish or prevent any undesirable increase in the speed of the motor while the 5 blades are at or near their zero pitch position. Correspondingly, when the propeller blades are moved in the direction of greater pitch, either forward or reverse pitch, the arm 7 moves in the direction of the arrow O 10 and thus opens the throttle sufficiently to maintain adequate engine speed under the greater load due to increase of propeller pitch.

In a similar manner arm 7 may be governed 15 as to movement and position by connection with a clutch or a gear shift mechanism so that when the engine is disengaged the arm will move in the direction of the arrow C and thus partly or entirely close the 20 throttle valve during disengagement, likewise moving in the direction of the arrow O and opening the throttle valve upon re-engagement of the engine power.

Figures 2 and 3 show my control mechanism 25 as adapted for governing the speed of flight or aircraft. For this purpose the arm 7 and shaft 8 are connected with a device having movable parts responsive to changes of pressure and relative velocity of the air. 30 I have represented this in the form of a pressure plate 27 carried on the forward end of a bar 28 slidably mounted in fixed supports 31 and 32. Spring 29 holds the pressure plate forward against pressure of the 35 wind or to the limit set by the collar 30. The arm 26 mounted on shaft 8 has its upper end divided to pass on either side of bar 28 and slotted to receive pin 33 passing through this bar. By this device an increase of 40 wind pressure moves the bar 28 backwards and acts through arm 26, shaft 8, arm 7, rod 9, lever 10, rod 11 and arm 2 to cut down the throttle opening and reduce the power. Similarly a decrease of speed by reducing 45 the pressure on plate 27 acts in the opposite manner to open wider the throttle valve and increase the engine power. Throughout these operations, however, the speed of 50 flight is fixed or altered by the position or movement of rod 12 under manual control. If rod 12 is moved forward towards the left this increases the throttle opening and thus the pressure plate 27 becomes operative to affect the throttle opening and control the 55 speed at this higher range of speed and pressure. In like manner a movement of rod 12 to the right reduces the throttle and fixes a lower level of speed but always under control of pressure plate 27.

While I have shown my engine control in 60 Figs. 2 and 3 as connected with a speed governing device actuated by a pressure plate, it is to be understood that this is illustrative, merely, and that any other form of speed 65 governor such as one acting on the principle

of the Pitot tube or an electro-magnetic device might be employed within the scope of my invention.

In Fig. 4 I have shown by diagram how my invention may be applied to control the 70 engine speed when reversing propeller pitch and at the same time to securing uniformity in the speed of flight. The amount of engine power is set by the manually operated rod 12 acting on lever 10 by moving its fulcrum 18 and thus acting on the throttle lever 2 through the connection 11. The connection 9, jointed and slidable in guides 17^a, connects with a second lever 10^a at its center portion 18^a. 19, 20, 21 and 37 represent the 80 mechanism operated in accordance with changes in propeller pitch as shown in Fig. 1, but acting on connection 9 indirectly through the member 10^a instead of directly as in Fig. 1. 27, 28, 33, etc., represent a pressure plate with its mechanism responsive to the speed of flight as shown in Fig. 2. This also acts on connection 9 through the combining member 10^a instead of directly as in Figure 2. Thus these two mechanisms exert 85 their combined influence on lever 10 in the same manner as each of them separately in Figures 1 and 2.

Having now fully described my invention, what I claim is:

1. The combination with a variable pitch propeller an engine and power-control means therefor, of a movable element coacting with the adjustment of said propeller, a lever, connections from said movable element to 95 said lever and from said lever to said power-control means for engine control in accordance with propeller pitch, and means for adjustment of the fulcrum of said lever whereby said power-control means may be 100 set for full power or part power without affecting the operation of said movable element as an engine control.

2. The combination with a variable pitch propeller an engine and power-control means 110 therefor, of a movable element coacting with the adjustment of said propeller, a slidably mounted member, a lever fulcrumed on said slidable member, connections from said movable element to said lever and from said lever to 115 said power-control means for engine control in accordance with propeller pitch, and means for adjustment of said slidable member whereby said power-control means may be set for full power or part power without 120 affecting the operation of said movable element as an engine control.

3. The combination with a variable pitch propeller an engine and throttle valve therefor, of a cam shaft adapted for angular movement corresponding with pitch adjustment of the propeller, a cam on said shaft, a movable arm actuated by said cam, a lever, connections from said movable arm to said 125 lever and from said lever to said throttle 130

valve for engine control in accordance with propeller pitch, and means for adjustment of the fulcrum of said lever whereby said throttle valve may be set wide open or partly open without affecting the operation of said cam and movable arm as an engine control.

4. The combination with an engine and power-control means therefor, of mechanism having a variable element, a slidably mounted member, a lever fulcrumed on said slidably member, connections from said variable element to said lever and from said lever to said power-control means, and means for adjustment of said slidable member whereby said power control means may be set for full power or part power without affecting the operation of said variable element as an engine control.

5. The combination with an engine and throttle valve therefor, of mechanism having a variable element, a lever, connections from said variable element to said lever and from

said lever to said throttle valve, and means for adjustment of the position of the fulcrum of said lever whereby said throttle valve may be set wide open or partly open without affecting the operation of said variable element as an engine control.

6. The combination with an engine and throttle valve therefor, of a plurality of variable mechanisms, a combining member adapted to be acted upon by the several mechanisms, a lever, connections from said combining member to said lever and from said lever to said throttle valve, and means for adjustment of the fulcrum of said lever whereby said throttle valve may be set wide open or partly open without affecting the operation of the several mechanisms through said combining member to control the engine.

In testimony whereof I hereunto affix my signature.

SPENCER HEATH.
